THOMAS GEORGE STILES, OF ARLINGTON, NEW JERSEY.

CIRCUIT CONTROLLER.

Application filed June 28, 1927. Serial No. 202,074.

This invention relates to circuit controllers for use in connection with railroad signal work. More particularly, the invention pertains to an electric circuit controller which is 5 adapted for use with a standard interlocking machine now in common use in railway practice. According to the invention the circuit controller is so connected to the interlocking machine that it is actuated by and upon operation of a lever latch handle which forms a part of the machine and which may be used to control switches, semaphores or the like.

Before proceeding with the description of the invention it will be necessary to refer to 15 the accompanying drawings in which:

Figure 1 is a side view of an interlocking machine with a circuit controller according to the invention attached thereto.

Figure 2 is an end view of the circuit controller.

Figure 3 is a front view of the circuit controller, the casing thereof being sectioned in order to show the interior of the controller.

Figure 4 is a side view of the same, the casting being sectioned in order to show the interior of the controller.

Figure 5 is a sectional view taken along the line 5—5 in Figure 3 and looking in the direction of the arrows.

30 Figure 6 is a detailed view of means for actuating a shaft, upon which are mounted the contact discs, by a shaft on the interlocking machine.

Figure 7 is an end view in detail of one of 35 the contact discs.

Figure 8 is a detailed view of a washer used to adjustably connect the contact discs.

Figure 9 is a sectional view taken along the line 9—9 in Figure 8 and looking in the direction of the arrows.

40 Figure 10 is a sectional view showing the manner of mounting the contact discs upon the shaft within the circuit controller and showing the manner of holding them in adjustable relation with each other.

Referring to Figure 1, the interlocking machine which is there illustrated comprises a lever a , pivoted as at a' , which may be used to throw switches or to operate semaphores 50 through the tail levers a^2 , a^3 . Movement of the lever a is controlled by the rocker die a^4 which is shown in abutment with the stop a^5 on the quadrant a^6 . The lever a may be moved to the right along the quadrant a^6 by depressing the latch handle a^8 thereby raising the 55 rocker die a^4 out of abutment with the stop a^5 .

The rocker die a^4 travels in the track a^9 in the rocker a^{10} and, therefore, when the rocker die a^4 is raised by depressing the latch handle a^8 , the rocker a^{10} will also be raised about its 60 pivot point a^{11} . The end a^{12} of the rocker a^{10} is connected through a universal joint to the link a^{13} which is connected at its other end with the locking shaft a^{14} . Movements of the end a^{12} of the rocker a^{10} will, therefore, cause 65 the shaft a^{14} to rotate in a manner which will be apparent. Depressing the latch handle a^8 to raise the rocker die a^4 over the abutment a^5 causes the end a^{12} of the rocker a^{10} to move through a certain distance. When the lever 70 a is pulled to the right, the rocker die a^4 will travel along the track a^9 and, since the radii of curvature of the track a^9 and the upper edge of the quadrant a^6 are the same, no movement will be imparted to the end a^{12} of the rocker 75 until the rocker die a^4 passes over the abutment a^5 , whereupon the latch handle a^8 will be released and the end a^{12} of the rocker be moved through a distance equal to that through which it was moved by raising the rocker die 80 a^4 over the abutment a^5 . In other words the end a^{12} of the rocker a^{10} is moved only upon depressing or releasing the latch handle a^8 . Of course, it then follows that the shaft a^{14} will be rotated at such times only. 85

There has been illustrated in Figure 1 only one of a plurality of levers all of which are mounted upon the base a^x in the same manner as the lever a and with all of which are similarly associated with shafts, such as a^{14} . 90 Movements of these shafts, and hence of the levers, are controlled by interlocking devices indicated in general at a^{15} , the action of which it is not necessary to set forth in detail for an understanding of this invention. 95

It is desirable, in an interlocking machine of the nature of that set forth above, to provide means for energizing or de-energizing certain electrical devices, such as polarizing relays, for instance, automatically upon 100 movement of the lever a . It is the principal object of this invention to provide such means. To this end, according to the preferred embodiment illustrated in the drawings, a circuit controller comprising a housing, in which is mounted a shaft carrying a plurality of contact discs, is mounted upon the interlocking machine in such a manner that movements of the locking shaft may be imparted to the shaft carrying the contact discs, thereby making or breaking certain 105 circuits in a manner which will appear later. 110

A further object of the invention consists in supplying suitable means to impart the movements of the locking shaft to the shaft upon which the contact discs are mounted. Still 5 another object consists in so mounting the contact discs upon the shaft that they may be readily adjustable with respect to one another so as to make or break whatever circuits it may be desired to make or break upon 10 movement of the shaft. Other objects of the invention will appear more clearly in the following description.

The circuit controller itself consists of a metal base b which is formed with lugs b' by 15 means of which it may be mounted upon the interlocking machine. The base is also formed with a hole b^2 therein through which may pass the locking shaft a^{14} . Perpendicular to the base and integral therewith are 20 formed pillar blocks b^3 which are provided with bearings for the shaft b^4 . A plurality of contact discs b^5 are mounted upon the shaft b^4 in a manner which will be described hereinafter.

25 A plurality of strips of insulating material b^6 are fastened to the base as by means of the lugs b^7 and the bolts b^8 . Upon the strips b^6 are mounted a plurality of contact springs b^9 , for co-operation with the contact discs, 30 and a corresponding number of binding posts b^{10} , for connection with outside wires (not shown).

The contact discs b^5 are formed of insulating material b^{11} having strips of metal b^{12} 35 embedded in a portion of their peripheries. They are drilled out as at b^{13} to the diameter of the shaft b^4 and have mounted on one side the notched discs b^{14} as by means of the rivets b^1 .

40 The discs are mounted upon the shaft b^4 with the sides upon which are mounted the notched discs b^{14} adjacent one another. Washers b^{16} are placed between the sides of the contact discs upon which are mounted the 45 notched discs b^{14} . The washers b^{16} are all formed with a tooth b^{17} which fit into the slot b^{18} in the shaft b^4 . The washers b^{16} are formed with projections b^{19} , b^{20} in their peripheries for co-operation with the notches in 50 the discs b^{14} . It will be seen that the contact discs may be adjusted to any angular position by merely separating them and turning them to any desired position. The projections b^{19} and b^{20} on the washers b^{16} are 55 formed on the discs so that one is one tooth space away from a diameter passing through the other. In this way a far greater degree of adjustability between adjacent contacts discs is secured. The discs are held in position upon the shaft b^4 between the bearing b^{21} and the nut b^{22} .

60 The circuit controller is adapted to be fastened to the interlocking machine by merely the bolts a^{16} and replacing them through the 65 lugs b' , the locking shaft a^{14} passing through

the hole b^2 into the interior of the controller. In order to transmit movements of the locking shaft a^{14} to the shaft b^4 , a clamp c is adapted to be fastened to the shaft a^{14} as by means of the stud c^6 and the bolt c^7 , the clamp c carrying a pin c' upon which is rotatably mounted the roller c^2 . The roller c^2 co-operates with the surfaces c^3 , c^4 in the cam c^5 which is carried with the shaft b^4 as by means of the set screw c^8 . The rollers c^2 is formed 75 with a spherical surface and fits exactly between the cam surfaces c^3 , c^4 in all positions of the cam so as to prevent any lost motion in transmitting the movement of the locking shaft a^{14} to the perpendicular shaft b^4 . 80 Space is left between the end of the roller and the inner surface c^9 of the cam in order to compensate for axial movements of the locking shaft a^{14} . It will be obvious, however, that other means, such as mitered gears, may 85 be used to transmit movements between the two shafts.

In order to prevent tampering the circuit controller may be provided with a housing d which may be locked in place by means of a 90 lock passing through the lug b^{23} formed on the base. The base is formed with holes b^{24} through which wires may be led to the binding posts.

95 It will now be apparent that movements of the locking shaft a^{14} , upon depressing or releasing the latch handle a^8 preparatory to swinging the lever a , are transmitted directly to the shaft b^4 which carries the contact discs for controlling any desired circuits. Thus 100 any desired circuits may be controlled automatically upon operation of the latch handle a^8 which must be moved before the lever a can be moved, and movements of which are, in turn, controlled by interlocking devices associated with the locking shaft a^{14} .

105 It will be seen that there has been provided a circuit controller having contact discs which may be adjusted to make or break any desired circuits automatically upon operation of the latch handle of a standard interlocking machine. This is accomplished without the necessity of altering in any way any of the parts of the standard interlocking machine and the whole construction is serviceable, 110 compact and easy of manufacture.

115 Nothing which has been said in the foregoing specification is intended as a limitation upon the scope of the invention except as indicated in the appended claims.

120 What I claim is:

1. In a circuit controller for use with an interlocking machine of the character described having a lever adapted to be moved upon movement of a latch handle, a rocker adapted to move upon movement of the latch handle, and a shaft independent of the controller adapted to rotate upon movement of the rocker, in combination, electric circuit control means in the controller, and means to 125

mount the controller in operative relation with said shaft, whereby said circuit control means will be actuated upon movement of the latch handle.

- 5 2. In a circuit controller for use with an interlocking machine of the character described having a lever adapted to be moved upon movement of a latch handle, a rocker adapted to move upon movement of the latch handle, and a shaft adapted to rotate upon movement of the rocker, in combination, a shaft rotatably mounted in the controller, electric circuit control means on said second named shaft, and means to transmit movements of the first named shaft to the second named shaft, whereby said circuit control means will be actuated upon movement of the latch handle.

10 3. In a circuit controller for use with an interlocking machine of the character described having a lever adapted to be moved upon movement of a latch handle, a rocker adapted to move upon movement of the latch handle, and a shaft adapted to rotate upon movement of the rocker, in combination, a shaft mounted rotatably in the controller, a plurality of electric circuit control means mounted on the second named shaft, means to mount the controller upon the interlocking machine at one end of the first named shaft, and means carried with the two shafts to rotate the second named shaft upon rotation of the first named shaft, whereby said circuit control means will be actuated upon movement of the latch handle.

15 4. In a circuit controller for use with an interlocking machine of the character described having a lever adapted to be moved upon movement of a latch handle, a rocker adapted to move upon movement of the latch handle and a locking shaft adapted to rotate upon movement of the rocker, in combination, a base formed with means to mount it upon the interlocking machine and a bearing therein to receive one end of the locking shaft, a shaft mounted rotatably upon the base, a plurality of electric circuit control means adjustably mounted on said second named shaft, and means to rotate the second named shaft upon rotation of the locking shaft, whereby said circuit control means will be actuated upon movement of the latch handle.

20 5. In a circuit controller for use with an interlocking machine of the character described having a lever adapted to be moved upon movement of a latch handle, a rocker adapted to move upon movement of the latch handle, and a locking shaft adapted to rotate upon movement of the rocker, in combination, a base formed with means mounted upon the interlocking machine and a bearing therein to receive one end of the locking shaft, a shaft mounted rotatably upon the base, electric circuit control means comprising a plu-

rality of contact discs mounted on said second named shaft, means to adjust the relative angular position of the contact discs with respect to each other, means to maintain the discs in adjusted position, means for connection with outside wires co-operating with the discs, and means to rotate the second named shaft upon rotation of the locking shaft, whereby said circuit control means will be actuated upon movement of the latch handle. 75

6. In a circuit controller for use with an interlocking machine of the character described having a lever adapted to be moved upon movement of a latch handle, a rocker adapted to move upon movement of the latch handle, and a locking shaft adapted to rotate upon movement of the rocker, in combination, a base formed with means to mount it upon the interlocking machine and a bearing therein to receive one end of the locking shaft, a shaft mounted rotatably upon the base, said second named shaft being disposed perpendicular to said first named shaft, electric circuit control means comprising a plurality of contact discs mounted adjustably on said second named shaft, notched discs mounted upon alternate proximate faces of the contact discs, means co-operating with the shaft and with the notched discs to hold the contact discs in adjusted relation upon the shaft, means for connection with outside wires co-operating with the discs, and means to rotate the second named shaft upon rotation of the locking shaft, whereby said circuit control means will be actuated upon movement of the latch handle. 85

7. In a circuit controller for use with an interlocking machine of the character described having a lever adapted to be moved upon movement of the latch handle, a rocker adapted to move upon movement of the latch handle, and a locking shaft adapted to rotate upon movement of the rocker, in combination, a base formed with means to mount it upon the interlocking machine and a bearing therein to receive one end of the locking shaft, a shaft mounted rotatably upon the base, said second named shaft being disposed perpendicular to said first named shaft, electric circuit control means comprising a plurality of contact discs mounted adjustably on said second named shaft, notched discs mounted upon alternate proximate faces of the contact discs, means co-operating with the shaft and with the notched discs to hold the contact discs in adjusted relation upon the shaft, means for connection with outside wires co-operating with the discs, and means to rotate the second named shaft upon rotation of the locking shaft, whereby said circuit control means will be actuated upon movement of the latch handle. 105

8. In a circuit controller for use with an interlocking machine of the character described having a lever adapted to be moved upon movement of a latch handle, a rocker adapted to move upon movement of the latch handle, and a locking shaft adapted to rotate upon movement of the rocker, in combination, a base formed with means mounted upon the interlocking machine and a bearing therein to receive one end of the locking shaft, a shaft mounted rotatably upon the base, electric circuit control means comprising a plu-

110 115 120 125 130

interlocking machine of the character described having a lever adapted to be moved upon movement of a latch handle, a rocker adapted to move upon movement of the latch handle and a locking shaft adapted to rotate upon movement of the rocker, in combination, a base formed with means to mount it upon the interlocking machine and a bearing therein to receive one end of the locking shaft, 10 a shaft mounted rotatably upon the base, a plurality of electric circuit control means adjustably mounted on said second named shaft, and self-compensating means to transmit rotation of the locking shaft to the second

named shaft comprising a clamp removably carried with the locking shaft, a cam having opposed cam surfaces removably carried with the second named shaft, a pin carried with the clamp, and a roller having a spherical surface adapted to maintain contact with both the cam surfaces in all positions of the cam, whereby said circuit control means will be actuated upon movement of the latch handle. 15

This specification signed this 10th day of 25 June, A. D. 1927.

THOMAS GEORGE STILES.
